US00D800798S

(12) **United States Design Patent** (10) **Patent No.:** **US D800,798 S**
(45) **Date of Patent:** **** Oct. 24, 2017**

(54) **PLOWING TINE TIP**

(71) Applicant: **Pearson Engineering Limited,**
Newcastle Upon Tyne (GB)

(72) Inventor: **Glen Stewart**, Washington (GB)

(73) Assignee: **Pearson Engineering Limited**, New
Castle Upon Tyne (GB)

(**) Term: **15 Years**

(21) Appl. No.: **29/541,431**

(22) Filed: **Oct. 2, 2015**

(51) LOC (10) Cl. **15-03**

(52) U.S. Cl.
USPC **D15/29**

(57) **CLAIM**

The ornamental design for a plowing tine tip, as shown and described.

DESCRIPTION

FIG. 1 shows a perspective view of a plowing tine tip, showing my new design, in a use condition;
FIG. 2 shows an alternate perspective view thereof;
FIG. 3 shows an alternate perspective view thereof;
FIG. 4 shows an alternate perspective view thereof;
FIG. 5 shows a front elevation view thereof, shown without environment;
FIG. 6 shows a rear elevation view thereof;

(Continued)

FIG. 7 shows a side elevation view thereof;
FIG. 8 shows a top plan view thereof; and,
FIG. 9 shows a bottom plan view thereof.

1 Claim, 9 Drawing Sheets
